BOTTLE RACK

Samuel S. Kaner, Tokyo, Japan, assignor to Premium Sales Kabushiki Kaisha, Tokyo, Japan

Filed Sept. 13, 1971, Ser. No. 180,243

Term of patent 14 years

Int. Cl. D6—04

U.S. Cl. D6—153

FIG. 1 is a side elevational view of a bottle rack embodying my new design;

FIG. 2 is a top plan view thereof;

FIG. 3 is a bottom plan view thereof;

FIG. 4 is a view similar to FIG. 1 but illustrating the manner of use of the rack in the storage of bottles and showing the bottles in phantom.

I claim:

The ornamental design for a bottle rack, substantially as shown and described.
